UNITED STATES PATENT OFFICE.

CHESTER LEROY HOOVER, OF CONVERSE, INDIANA.

BASKET.

Application filed July 27, 1922. Serial No. 577,950.

To all whom it may concern:

Be it known that I, CHESTER L. HOOVER, a citizen of the United States, residing at Converse, in the county of Miami and State 5 of Indiana, have invented a new and useful Basket, of which the following is a specification.

This invention aims to provide a bottom for a basket, which will reinforce the basket 10 and hold the contents of the basket out of contact with the ground, the construction being such that the standards of the basket will not burst out around the bottom of the basket, it being possible to make parts of 15 the bottom of the basket out of waste lumber, the construction being such that the basket will have a firm and secure base and will not be likely to be tipped over.

It is within the province of the disclosure 20 to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the 25 precise embodiment of the invention shown can be made without departing from the spirit of the invention.

In the accompanying drawings:—

Figure 1 shows in side elevation, a basket 30 constructed in accordance with the invention; Figure 2 is a bottom plan; Figure 3 is a section taken through a portion of the bottom of the basket on the line 3—3 of Figure 2; Figure 4 is a top plan of the bottom of the basket; Figure 5 is a cross section; Figure 6 is a section on the line 6—6 of Figure 4.

The body of the basket is denoted by the numeral 1 and comprises spaced vertical 35 standards 2 wherewith circumferential strips 3 are interlaced. The upper ends of the standards 2 are received between an inner band 4 and an outer band 5 connected by securing elements 6 which pass through the 40 upper ends of the standards 2.

The bottom of the basket is denoted generally by the numeral 9 and includes a main frame comprising side members 8 and end members 9 located between the side members 10. A brace 10 extends between the 45 end members 9. The brace 10 may be

omitted if desired. Securing elements 11 pass through the end members 9 and engage the brace 10 to hold the brace in place, as shown in Figure 3. Securing elements 12 60 pass through the side members 8 and engage the end members 9, as shown in Figure 6. The standards 2 extend downwardly on the outside of the main frame, as shown in Figure 3.

On the main frame is mounted a panel 65 comprising interlaced strips 14 and 15. The ends of the strips 14 rest on the side members 8. The ends of the strips 15 rest on the end members 9.

On the ends of the strips 14 and 15 of the panel is superposed an auxiliary frame 70 made up of side members 16 and end members 17. The side members 16 of the auxiliary frame are disposed above the side members 8 of the main frame. The end members 17 of the auxiliary frame are disposed above the end members 9 of the main frame. A strip 18 extends across the panel 75 and is located above the brace 10. Securing elements 18 connect the main and auxiliary frames and pass through some or all of the constituent strips 14 and 15 of the panel. A band 20 is located about the lower ends 80 of the standards 2 of the body 1. Securing elements 21 pass through the band 20 and enter the main frame 8—9.

The basket will be strong and substantial, owing to the specific construction of the bottom 7, and waste lumber, not available for 90 any other purpose, may be used in the making of the main frame. The basket always will present a flat bottom, and will not tip over, nor will the panel 14—15 sag downwardly to any appreciable extent. Figure 95 5 will render it evident that the panel is elevated enough so that the contents of the basket will be held well away from the support on which the basket is mounted, the contents of the basket being kept dry and 100 clean.

It will be understood that the construction described may be used in connection with a hamper, a market basket, or any sort of a basket other than the elongated clothes 105 basket depicted in the drawings.

What is claimed is:—

1. A basket comprising a bottom including a main frame; a panel supported on the main frame; an auxiliary frame superposed on the panel; securing elements connecting the frames and engaging the panel; a body

extending downwardly about the main frame; and means for securing the body to the periphery of the main frame.

2. A basket comprising a bottom including a main frame; a panel supported on the main frame; an auxiliary frame superposed on the panel; securing elements connecting the frames; a body extended downwardly about the main frame; a binder surrounding the body in alignment with the main frame;

and securing elements connecting the binder, the body and the main frame.

In testimony that I claim the foregoing as my own, I have hereto affixed my signature in the presence of two witnesses.

CHESTER LEROY HOOVER.

Witnesses:

JAMES S. DECKER,
W. D. HOOVER.
